United States Patent Office

Des. 208,622
Patented Sept. 19, 1967

208,622

SOCK

Harold V. Jensen, 911 Trenton St.,
High Point, N.C. 27260

Filed June 15, 1966, Ser. No. 2,691

Term of patent 14 years

(Cl. D2—331)

FIG. 1 is a side elevational view of a sock showing my new design; and

FIG. 2 is a side elevational view of the side opposite thereto.

I claim:

The ornamental design for a sock as shown.
